UNITED STATES PATENT OFFICE.

LOUIS FRIEDMAN, OF NEW YORK, N. Y.

NECKTIE.

Application filed November 13, 1924. Serial No. 749,612.

This invention relates generally to neckties, having more particular reference to the type of necktie commonly known as a bow tie, the invention being embodied in a ready made bow tie.

The invention has for an object to provide a novel form of bow tie whose shape may be changed to suit the fancy of the user, a further object relating to the provision of means permitting substitution of different bow elements.

For further comprehension of the invention and of the objects and advantages thereof, reference will be had to the following description and accompanying drawing, and to the appended claim in which the various novel features of the invention are more particularly set forth.

Fig. 1 of the drawing is a face view of my improved bow tie.

Fig. 2 is an edge view thereof.

Fig. 3 is a similar view to Fig. 1, but showing a modification.

Fig. 4 is a side view of the crosspiece clip.

Fig. 5 is an end elevational view thereof.

Fig. 6 is a side elevational view of the element from which the bows of the tie are formed.

In constructing my improved tie I make use of strip 10 of the material known as chenille, or like material which consists of hair or hair-like strands caught between a pair of twisted wires 10', or made of fur or any similar material having a fuzzy or fur-like appearance, this strip being of suitable length to have its ends doubled backward in the general plane of the tie to form the bows of the tie. This material possesses both ornamental properties, and is also characterized by a limited degree of flexibility that permits it to be readily bent while retaining the configuration that may be given it, the material being in effect of a semi-rigid nature. The ends of the strip are secured down upon the intermediate portion by a crosspiece 12, to which the usual neckband 13 is attached. By means of the construction above set forth a tie is provided whose wings or bows may be readily adjusted to any desired shape, and will retain the given shape or configuration, by reason of the semi-rigid nature of the material.

In Fig. 3 I have shown a tie which comprises two of the chenille strips arranged

one behind the other and secured by the 55 one cross-piece, the two strips being of different color, one of the strips being indicated at 10^a and the other at 10^b. With this arrangement a considerable variation of the appearance of the tie can be effected as 60 the front and back elements can be bent to expose different portions of the back element.

I may also provide, in connection with my improved tie, and particularly in connection with the form of tie shown in Fig. 3 of the drawing, a form of crosspiece that permits of ready interchangeability of the bow or wing elements. To this end I provide a clip 16 that is curved to elliptical form 65 in end view and has its ends separated as shown, these ends being formed with slotted apertures 17. In these apertures 17 are engaged the hooks 18 projected from opposite sides of the filler bar 19 to which the 70 neckband 13 is attached. As shown in Fig. 4 of the drawing the ends of the clip 16 abut against the sides of the bar 19, and the clip must be compressed to have one end 75 thereof swing upon the adjacent hook as a pivot, in order to free the bar from the clip for insertion or replacing of the two elements 10^a and 10^b. It will be understood of course that the clip 16 will be covered by a suitable ornamental facing strip such as indicated at 12'. This construction permits of interchanging the two elements 10^a, 10^b or the substitution of one bow-forming element for another in the tie.

Having thus described my invention, what 80 I claim as new and desire to protect by Letters Patent of the United States is as follows:—

A ready made bow tie comprising a pair 85 of bow elements arranged one in front of the other, each of said bow elements being comprised of a strip of chenille, said strips having their ends turned backward to form the bows of the tie, and a crosspiece in the form of a removable clip securing the said 90 strips in place, said clip comprising a sheet element of parti-elliptical form, and a filler bar located between the ends of the said sheet element and having hooks projected therefrom and engaging the latter.

In testimony whereof I have affixed my signature.

LOUIS FRIEDMAN.
